BALL-POINTED PEN

Leslie Coler-Dark, Flushing, N. Y., assignor to
 Universal Fountain Pen & Pencil Company,
 New York, N. Y., a copartnership

Application August 7, 1948, Serial No. 43,089

3 Claims. (Cl. 120—42.03)

1

This invention relates to ball-pointed pens of the retractile type, and has for one object the provision of such a pen in which the writing unit, consisting of ball tip and ink reservoir, may be removed from and replaced through the front end of the pen barrel without interfering with the retracting mechanism. In attaining this object I place the retracting mechanism at the upper end of the pen and provide it with a slidable clamping member, between the forwardly extending spring jaws of which the upper end of the writing unit is removably held. The spring, which normally maintains the writing unit in retracted position and the force of which the writer must overcome to project the tip beyond the barrel and into writing position, is placed within a cap, slidable with reference to the barrel, and acts upon it and the barrel, the cap in turn being connected with the slidable clamping member. A latch is provided to hold the unit in writing position against the thrust of the spring. When the latch is released the spring normally retracts the unit; however, further pressure exerted by the writer upon the cap will project the tip beyond the writing position where it may be readily grasped and withdrawn from the jaws of the clamping member and replaced by a refill.

A further object of my invention is to provide a sturdy, serviceable pen with a simple retracting mechanism, easily operated and not easily put out of order.

In the accompanying drawings I have illustrated a preferred embodiment of my invention, all the parts shown being made of metal. In these drawings

Figure 1 is a longitudinal section through a retractile ball-pointed pen made in accordance with my invention and showing the writing unit in retracted position;

Figure 2 is a view similar to Figure 1 showing the writing unit projected with the tip in writing position and held in place by the latch;

Figure 3 is similar to the preceding views, but showing the writing unit projected even further so that it may be withdrawn for replacement;

Figure 4 is a longitudinal section through the slidable clamping member showing the construction of the latch bolt;

Figure 5 is an end elevation of the clamping member in Figure 4; and

Figure 6 is a plan view of a sleeve which is mounted upon the upper end of the barrel and is provided with a keyhole slot.

The pen illustrated in these drawings comprises a barrel 1, having a tapered lower end 2

2

terminating in an opening 3. Fixed upon the upper end of the barrel, and constituting, in effect, an extension of it is a slotted sleeve 4, within which is mounted a slidable clamping member 5. Fitting over both the sleeve and the upper end of the barrel and slidable thereon is a cap 6 connected to the clamping member by means of a pin 7. Overlying the upper end of the sleeve 4 is a disk 8 against which abuts a compression coil spring 9, the other end of which abuts against the inner upper end of the cap 6. The sleeve 4 is provided with a keyhole slot 10 through which the connecting pin 7 extends, the slot enabling the cap to be moved longitudinally with reference to the barrel and sleeve. The slot is provided near one end with a circular enlargement 11, whose function will be presently described.

The slidable clamping member 5 comprises a cylindrical block 12, into which the pin 7 is fitted, having a bore 13 in which a latch bolt 14 is slidably mounted. This bolt comprises a latch pin 15 and a block 16, the underface of the block being countersunk for the reception of a small compression coil spring 17, the lower end of which bears against a pin 18 which spans the lower open end of the bore 13. This bore is provided at its upper end with an overhanging annular shoulder 19 which acts as a stop for the bolt, the block 16 being provided with a corresponding annular shoulder 20. As shown in Figure 4, the bolt is in its outermost position, but it can be pushed down into the bore 13 against the slight pressure of the coil spring 17. Two opposed spring jaws 21 extend forwardly from the block 12. These are curved transversely, as shown in Figure 5, and are provided with flaring ends 22 for the ready reception of the writing unit, as will be explained presently.

The writing unit comprises a tubular, open-ended ink reservoir 23 on the lower end of which is mounted a conical tip 24 terminating in a socket which holds a writing ball 25. The upper end of the ink reservoir is inserted between and frictionally held by the clamping jaws 21, being guided between them by the flaring ends 22. As writing pressure will force the writing unit upward until the upper end of the reservoir engages the adjacent face of the block 12 of the clamping member, I provide that face with an air vent 26 which communicates with the bore 13 and gives free access of air to the interior of the reservoir.

As shown in Figure 1, the latch pin 15 extends loosely through a hole 27 in the cap 6 and also through the slot 10 of the sleeve 4. The width

of this slot for most of its length is slightly wider than the diameter of the pin 7 and latch pin 15, but is narrower than the block 16 which constitutes the body of the bolt 14. Thus, as shown in Figure 1, when the writing unit is retracted, the bolt is depressed through the action of the overhanging walls of the sleeve 4, adjacent the slot 10, the upper end of the latch pin lying substantially flush with the outer face of the cap. The upper end of the cap is provided with a pocket 10 clip 28 of conventional design, the lower end of which overlies the outer end of the latch pin, as shown in Figure 1.

The pen is operated as follows—starting with the parts in the position shown in Figure 1: When the writer desires to project the tip of the writing unit beyond the barrel in order to use it, he telescopes the cap and barrel against the resistance of spring 9. Pin 7 and latch pin 15 slide along the slot 10. As the clamping member 5 carrying the bolt 14 moves downwardly in the barrel, the bolt, following the slot 10, ultimately comes into registry with the circular enlargement 11 which serves as a catch, whereupon spring 17 snaps the bolt outwardly and into this catch, as shown in Figure 2, the latch pin projecting beyond the cap, thus pressing against the lower end of the clip and swinging it upwardly. In this position the pen is ready for writing with its parts latched in that position. In order to release the latch, it is only necessary for the writer to press down upon the clip—or if there is no clip, then upon the projecting latch pin—thereby pressing the bolt back into the bore 13 and out of the catch 11, permitting the compressed coil spring 9 to return the parts to the position shown in Figure 1.

Replacement of an empty writing unit with a refill is effected as follows: The writer, starting from the position of Figure 1 telescopes the cap and the barrel and, by exerting continued pressure on the clip to prevent latching, moves the parts from the position Figure 1 to the position Figure 3 with the lower end of the unit projecting beyond normal writing position, whereupon it is grasped between finger and thumb and withdrawn from the barrel. While the parts are still in the position shown in Figure 3, a refill is inserted through the opening 3, until its upper inner end is clamped between the spring jaws 21, being guided thither by their flared ends 22.

The great advantage of this pen is that an old writing unit may be replaced by a new one through the lower open end of the barrel without in any way disturbing the retracting mechanism which is located at the other end of the pen. Moreover, the retracting mechanism is simple in construction and not easily put out of order.

I claim:

1. A ball-pointed pen comprising a barrel having an open lower end; a ball-tipped writing unit in the barrel, a clamping member in the barrel having opposed spring jaws for removably holding the writing unit, a cap slidably mounted on the barrel, a pin connecting the clamping member with the cap, the barrel having a longitudinal slot for receiving the connecting pin and of such length as to permit projection of the writ-

ing unit beyond writing position and retraction of it within the barrel, latching means for holding the writing unit in writing position, and a compression spring in the cap urging the cap away from the barrel for retracting the unit within the barrel when the parts are unlatched.

2. A ball-pointed pen comprising a barrel having an open lower end, a ball-tipped writing unit in the barrel, a clamping member in the barrel having opposed spring jaws for removably holding the writing unit, a cap slidably mounted on the barrel, a pin connecting the clamping member with the cap, a spring-pressed latch bolt carried by the clamping member, a latch pin on the bolt, the barrel having a longitudinal slot for receiving the connecting pin and the latch pin, said slot having an enlargement therein constituting a catch for receiving the bolt and holding the writing unit in writing position with its tip projecting from the open lower end of the barrel, the cap having a hole therein through which the latch pin projects when the latch bolt is in the catch and whereby the bolt can be slid from the catch, and a compression spring in the cap pressing against the upper end of the barrel and the upper inner end of the cap for moving the cap upwardly and retracting the unit within the barrel when the parts are unlatched.

3. A ball-pointed pen comprising a barrel having an open lower end, a ball-tipped writing unit in the barrel, a clamping member in the barrel having opposed spring jaws for removably holding the writing unit, a cap slidably mounted on the barrel, a pin connecting the clamping member with the cap, a spring-pressed latch bolt carried by the clamping member, a latch pin on the bolt, the barrel having a longitudinal slot for receiving the connecting pin and the latch pin, said slot having an enlargement therein intermediate its length constituting a catch for receiving the bolt and holding the writing unit in writing position with its tip projecting from the open lower end of the barrel, the cap having a hole therein through which the latch pin projects when the latch bolt is in the catch and whereby the bolt can be slid from the catch, and a compression spring in the cap pressing against the upper end of the barrel and the upper inner end of the cap for moving the cap upwardly and retracting the unit within the barrel when the parts are unlatched, the portion of the longitudinal slot below the enlargement permitting projection of the writing unit beyond writing position whereby the writing unit may be grasped and removed.
